AUTOGRAPHIC REGISTER

William R. Wright, Lincoln, Nebr.

Application January 21, 1935, Serial No. 2,731

4 Claims. (Cl. 282—1)

My invention relates to autographic registers and more particularly to the pegs employed for entering the apertures of the superposed sheets of paper, a primary object of the invention being to provide a peg of novel form and structure.

Another of my objects is the provision of a peg which is wedge shaped from front to rear when it enters the apertures of the superposed sheets of paper and which has vertical front and rear edges while the entry is being made on the memoranda sheets.

Another of my objects is the provision of an expansible peg which freely enters the apertures of the superposed sheets of paper and which is expansible for perfectly aligning all of the apertures in both longitudinal and transverse directions so as to provide substantially perfect registration of the superposed strips of paper.

Another of my objects is the provision of an expansible and contractible peg in which both movements of expansion and contraction are automatic.

Having in view these objects and others which will be pointed out in the following description, I will now refer to the drawing, in which

Figure 1 is a plan view of my autographic register, portions being torn away to show the bearings for the crank shaft and the spring for maintaining the crank shaft in its normal position.

Figure 2 is a view in side elevation of the spring and showing its relation to the crank shaft, portions of the casing walls being also shown.

Figure 3 is a view in side elevation showing the peg in its expanded position to completely fill the apertures of the memoranda sheets which are used in the autographic register.

Figure 4 is a view similar to Figure 3 but showing the peg in the position where it is ready to enter the apertures of the memoranda sheets.

Figure 5 is a vertical sectional view of a fragment of the casing showing a modified form of opening and closing mechanism for the peg.

Figure 6 is a view similar to Figure 5 and showing the same modification but showing more clearly the peg alone and in its relation to the bar.

The autographic register has a rectangular case 10 similar in size and dimensions to many of the autographic registers which have heretofore been patented. The top wall of the casing is provided with a rectangular aperture and underneath this is a writing table 11 which is usually of sheet metal construction. As is usual in this type of apparatus the superposed sheets of paper with carbon papers between them are fed over the

writing table. These sheets of paper are in the form of long strip which are usually weakened on transverse lines, the sections thus formed being provided with identical or otherwise registering indicia so that the entry on the top section will be duplicated on all of the sections underneath the top section. 5

The strips of paper are provided with apertures as is well known in the art for temporarily securing them together and in registration while 10 the entry is being made. It is very important that perfect registration may be obtained and held during the entry of the memoranda in order to prevent errors such for example as the placing of numerals in the cents column of the carbon 15 copy and in the dollars column of the top section as is liable to occur if the sheets are not in perfect registration. Various constructions for obtaining registration have been employed in the prior devices but these constructions usually relate to variations in the tensioning of the strips 20 of paper. Instead of the usual tensioning devices I employ pegs which are designed to entirely fill the front and rear portions of the circular apertures in the strips of paper. 25

The pegs project through apertures in the writing table 11 and their preferred form is that shown in Figures 3 and 4. Each peg 12 consists of two halves which are pivotally secured together, the pivots being secured to the writing table 11 or 30 to a reenforcing bar which is secured to the writing table 11. For opening and closing the pegs 12 into the Figure 3 and Figure 4 positions I employ a bar which is rigidly secured to a shaft 13, the shaft being journaled at 14 to fixed portions of 35 the frame of the casing. As shown in Figure 1, the shaft 13 has the crank end against which rests the free end of a leaf spring 16 as most clearly shown in Figure 2. The tendency of the spring is to maintain the crank end of the shaft 13 in its 40 lowermost position.

As shown in dotted lines in Figure 1, the individual parts of the pegs 12 are each segmental in horizontal section and less than a semi-circle. Referring now to Figure 3 it will be seen that the 45 bar 17 is rigidly secured to the shaft 13 and that the bar may be rocked manually about the axis of the shaft 13 toward and away from the pegs 12. For convenience in grasping the bar 17 it is provided with a shallow groove in its forward edge 50 for receiving the tip of a finger. This groove extends to at least the lower edge so as to provide a cutting edge for tearing off the strips of paper. The bar 17 is furthermore provided with a cut-away portion 18 for surrounding the upper por- 55

tions of the peg 12 and in this cutaway portion is a knob 19 which projects downwardly beyond the plane of the lower surface of the bar 17. It will readily be apparent that when the parts are moved from the Figure 4 position the lowering of the bar 17 will cause the knob 19 to engage the two parts of the peg 12 to spread them apart into the Figure 3 position. The front and rear walls of the pegs 12 are substantially vertical in the Figure 3 position and the distance between them is substantially equal to the diameter of the circular apertures in the strips of paper. This will cause the pegs in expanding to align the strips of paper into perfect registration with each other and to hold them firmly in such registration until the parts of the pegs 12 are again brought together into the Figure 4 position.

It should be noted that the aligning of the peripheries of the apertures in the strips of paper is due not only to the movements of the pegs but also to their shape. The outer surfaces of the parts of the peg are cylindrical and they have the same radius of curvature as that of the apertures. The inner surfaces of the parts of the peg are flat to facilitate bringing them into the closed position as shown in Figure 4. The peg as a whole is thus wedge shaped for entering the apertures but after expansion it is cylindrical as shown in Figures 1 and 3. The expansion of the peg in the apertures of the paper causes a shifting of the individual strips of paper not only in a forward and rearward direction but rather in all directions away from the center of curvature of the cylindrical surfaces, the result being that the circular apertures of the superposed sheets are brought into perfect peripheral alignment which determines the perfect registration of the superposed sheets relative to their indicia.

The bar 17 may be lowered manually but the spring 16 will accomplish the lowering of the bar 17 as soon as the finger is released from the edge of the bar 17. This lowering of the bar 17 is thus automatic. Means are also provided for automatically drawing the parts of the pegs together when the bar 17 is lifted to withdraw the knob 19 from between the upper portions of the peg 12. The means which I show consist of a leaf spring 20 underneath the writing table, the spring 20 having a knob 21 secured thereto at its free extremity. The knob 21 thus acts at all times against the lower portions of the parts of the peg 12 with a tendency to spread the lower parts and to thereby cause the upper parts to come together. Whenever the bar 17 is lifted the action of the spring 20 becomes operative immediately to bring the peg 12 into its position for engaging the apertures of the strips of paper.

Just by way of illustration I show in Figures 5 and 6 one of the many possible optional constructions for accomplishing the same results. The pegs 12' in this case are not directly pivoted together but they are individually secured to shafts 22 which are journaled against the lower surface of the writing table 11'. Each shaft 22 has an arm 23 secured thereto, the arms projecting in the direction of each other and each arm being slotted to receive a pin 24 which is secured to an arm 25. By means of the arm 25 the pin 24 may be made to rise and fall to thus positively actuate both arms 23 and their shafts 22 to thereby positively actuate the parts of the peg 12' to opening and closing position.

The rod 26 is slidably secured through suitable apertures in the brackets 27 and 28 depending from the frame of the register. Limiting stops

29 and 30 are secured to the rod 26 for limiting the movement of the rod in both directions, the limits of movement being determined by the contacts of the stop 29 with the bracket 27 and of the stop 30 with the bracket 28. The lower end of the link 25 is pivotally secured to the stop 29 so that the movement of the rod 26 in one direction will cause the pivot 24 to rise and the movement of the rod 26 in the other direction will lower the level of the pivot 24. The rod 26 is also provided with a slidable collar 31 which is movable relative to the rod 26. A coiled spring 32 surrounds the rod 26 between the stop 29 and the collar 31.

The bar 17' is similar to the bar 17 in the previously described construction. It is similarly secured to a shaft 13' and it has a similar range of movement between the horizontal and inclined positions as shown in Figures 4 and 5. The arm 33 is secured to the shaft 13' as shown in Figure 20 so that the arm 33 is rocked in response to the movements of the bar 17'. The arm 33 is slotted for the reception of a pin 34 projecting from the slidable collar 31.

The movements of the link 25 are therefore confined to definite limits in response to the movements of the bar 17' and the structure also provides for considerable play or idle movement of the bar 17' before it begins to actuate the link 25. When the peg 12' is in its closed position as shown in Figure 5 the bar 17' is in its open position and the arm 33 is in the full line position as shown in that figure. When the bar 17' is lowered to its horizontal position, the arm 33 will move into the dotted line position. This movement will be idle as respects the link 25 until the slidable collar 31 comes into contact with the fixed abutment 30. At this point the abutment 30 will be moved toward the right, its movement in this direction being limited by the bracket 28. It is during this movement of the abutment 30 and the resulting movement of the rod 26 that the rod 26 is also moved in the same direction to thus force the pivot 24 to move upwardly to thereby expand the peg 12'. When the bar 17' is lifted to its full line position in Figure 5 the movement of the rod 26 is reversed to cause the movement of the link 25 to its lowermost position as shown in full lines in Figure 5. In this position the peg 12' is closed as shown. A spring 35 is employed to function in the manner of the spring 16 to normally maintain the bar 17' in its horizontal position.

The mechanism thus provides a double stop for limiting the opening movement of the peg 12'. At the maximum opening of the peg 12' the stop 30 is in contact with the bracket 28 and the bar 17' is in its fully closed position. The parts are thus rigidly fixed in the movements following the closing of the bar 17' but they are made yieldable for the opening of the bar 17' and the resulting closing movement of the peg 12'. During the opening movement of the bar 17' the force transmitted from the collar 31 to the stop 29 acts through the yieldable spring 32. When the stop 29 contacts with the bracket 27, further opening movement of the bar 17' will simply compress the spring 32 and expand the spring 35. By means of this construction the mechanism is not subjected to any undue strains when the bar 17' is raised beyond the position which determines the closing of the peg 12'.

Having thus described my invention in such full, clear, and exact terms that its construction and operation will be readily understood by others

skilled in the art to which it pertains, what I claim as new and desire to secure by Letters Patent of the United States is:

- 5 1. In combination with the writing table of an autographic register for supporting a plurality of superposed sheets of paper having circular apertures, a peg consisting of a pair of complementary parts pivotally secured underneath the writing table and projecting upwardly there-through for movement of the upper portions of said parts toward and away from each other whereby said pegs may be contracted to a size smaller than the apertures in the paper to facilitate the passage therethrough and said pegs may 10 be expanded to an external distance between them substantially equal to the diameter of the circular apertures of the superposed sheets of paper.
- 15 2. A peg for autographic registers, said peg consisting of a pair of complementary parts having a rocking relation relative to each other, each of said parts having a flat inner surface and a convex outer surface, the curve of the outer surface being that of a portion of a circular cylinder whose radius is substantially that of the radius of the circular aperture of the superposed sheets of paper which are fed through the autographic register.
- 20 3. A peg for autographic registers, said peg

consisting of a pair of complementary parts having a rocking relation to each other whereby they may be drawn together to collapse said peg or spaced apart to expand said peg, said peg having vertical front and rear walls when expanded 5 and having its front and rear walls inclined upwardly and toward each other when collapsed, means under the control of the operator for expanding said peg, and means responsive to the release of said peg expanding means for automatically collapsing said peg.

4. A peg for an autographic register having a writing table, said peg consisting of a pair of like parts pivotally secured together underneath the writing table and projecting upwardly there-through, the inner surfaces of said peg parts being each in the form of a dihedral angle with the pivotal axis positioned at the vertex of the dihedral angle, a bar pivotally secured above said peg, a knob on said bar for operation between 20 the upper portions of said parts for expanding the upwardly projecting portion of said peg when said bar is lowered, and a spring pressed knob bearing against the lower portion of said peg and operative between the parts thereof to spread the 25 lower portions of said peg and to thereby cause the upper portions of said peg to approach each other when said bar is lifted.

WILLIAM R. WRIGHT.
